UNITED STATES PATENT OFFICE.

FRED M. LOCKE, OF VICTOR, NEW YORK.

INSULATOR.

No. 852,730.

Specification of Letters Patent.

Patented May 7, 1907.

Application filed November 16, 1903. Serial No. 181,361.

To all whom it may concern:

Be it known that I, FRED M. LOCKE, of Victor, in the county of Ontario, in the State of New York, have invented new and useful improvements in Insulators, of which the following, taken in connection with the accompanying drawings, is a full, clear, and exact description.

This invention relates to improvements in high potential insulators in which two or more porcelain or equivalent parts are fitted or nested one into the other and secured together at the joints by fusing, cementing or equivalent means and are then fitted upon and secured to the center support, so that the intermediate section extends below the top and center piece.

The object is to maintain a maximum insulation at or near the point of securement of the electric conductor to avoid puncturing by the electric current and at the same time to protect the supporting pin from current leakage without extending the center to the base of the pin, thereby saving material and enabling the center to be more easily and accurately formed. Other objects will appear hereafter.

In the drawings—Figure 1 is a vertical sectional view of my improved insulator, and Fig. 2 is an inverted plan of the same.

Similar reference characters indicate corresponding parts in all the views.

As seen in the drawings, this insulator comprises a top section —1—, an intermediate section —2— and a center section —3—, all of which are formed of porcelain or equivalent material and are fitted or nested one into the other and fused or otherwise secured by suitable filling in the joints to form a substantially integral insulator.

The top section is concavo convex or bell shape in cross section and is preferably of greater diameter than the intermediate section, being arranged with its convex face uppermost and provided with a grooved central boss —4— to which the electric conductor is attached while its lower face is formed with a central socket which receives the upper end of the section —2— and also receives a suitable material such as glaze which fills the intervening space and permanently secures the contiguous parts together. This latter section —2— is preferably bell-shaped and extends downwardly a considerable distance below the top —1— or to a point between the lower face of the top —1— and a

supporting cross arm or equivalent device, as —5—, shown by dotted lines, Fig. 1, and also extends beneath the lower end of the center piece —3—, the upper portion being abruptly swelled outwardly at —6— under the lower face of the section —1— to form additional support therefor and also to carry the static discharge away from the center pin. Although I have shown and described this intermediate section as a single piece, it is apparent that it may be made up of two or more pieces nested one within the other if desired.

The inner or center section —3— is fitted and secured within the socket in the upper end of the intermediate section —2— and its lower end preferably terminates in a plane between the ends of both of the sections —1— and —2—, or rather above their lower ends and is formed with an interior threaded socket —7— for receiving a supporting pin —8— shown by dotted lines Fig. 1.

It is now seen that the greatest thickness of insulating material is interposed between the upper end of the pin —8— and points of securement of the electric conductor so as to afford ample resistance against shunting or short circuiting of the current from the conductor to the pin, and it is also apparent that the skirt of the depending portion of the section —2— which surrounds the pin —8— prevents the leakage of the current from reaching said pin and by terminating the section —3— a considerable distance above the bottom of the section —2— and thereby increasing the air gap between the base of the section —2— and pin —8— the center section is protected from moisture so that the current leakage cannot creep over its surface to the base of the pin. It will be seen that this air space between the pin and inner face of the part —2— is substantially uniform from top to bottom, that is, the inner face of the part —2— is substantially parallel with the outer face of the pin —8. The object of this is to distribute the static discharge of the electric current evenly from the junction of the parts —1— and —2— to the base of the part —2—, thereby neutralizing its force and preventing serious injury to the pin.

It will be observed that the center piece —3— is cylindrical and comparatively short, which saves material and enables it to be more easily and accurately formed, and that the base of the reduced head of the section —2— flares abruptly from and above the

lower end of the center-piece and terminates in a comparatively long skirt, which extends some distance below the center-piece and has its lower edge resting on the cross-arm, but separated from the pin —8— so as to leave an intervening air space extending from the base of the pin to the center-piece. The object of this is two-fold, first, to keep the moisture away from the pin —8—, and particularly from the junction of the pin with the cross-arm, and second, to afford a considerable air space as well as thickness of insulating material between the top face of the section —1— and head of the pin —8— to avoid as far as practicable the leakage of the electric current from the more or less moist surface of the cap —1— to the pin —8—.

Having thus described my invention what I claim and desire to secure by Letters Patent is—

A porcelain insulator comprising a short cylindrical center piece —3— having a

threaded socket extending upwardly from the bottom, a bell-shape skirt fitted upon and secured to the top and sides of the center piece and having portions thereof flaring abruptly from and above the bottom of the center piece, said skirt extending downwardly some distance below the lower end of the center piece, in combination with a cross arm and pin, the latter entering said center piece, and said skirt extending from the center piece to the cross arm around the pin and of greater interior diameter than said pin between the center piece and cross arm to afford considerable air space thereby preventing burning out of the base of the pin.

In witness whereof I have hereunto set my hand this 12th day of November 1903.

FRED M. LOCKE.
